UNITED STATES PATENT OFFICE.

FRANK C. SMITH, OF MINNEAPOLIS, MINNESOTA.

VENTILATOR ATTACHMENT.

1,352,843.

Specification of Letters Patent. Patented Sept. 14, 1920.

Application filed January 25, 1917. Serial No. 144,335.

To all whom it may concern:

Be it known that I, FRANK C. SMITH, a citizen of the United States, resident of Minneapolis, county of Hennepin, State of Minnesota, have invented certain new and useful Improvements in Ventilator Attachments, of which the following is a specification.

The object of my invention is to provide an attachment for a ventilator or flue which will operate as a means for increasing the draft and hastening the discharge of the currents of air from the ventilator.

A further object is to provide a ventilator attachment of comparatively simple construction and one which can be applied to an ordinary ventilator at a comparatively small expense.

A further object is to provide an attachment which may be used in connection with a chimney flue.

The invention consists generally in various constructions and combinations, all as hereinafter described and particularly pointed out in the claim.

In the accompanying drawings forming part of this specification,

Figure 1 is an elevation, partially in section, of the upper portion of a ventilator with my invention applied thereto,

Fig. 2 is a sectional view, showing the position of the attachment on the ventilator and the means for imparting a rotary movement to the currents of air,

Fig. 3 is a view looking at the exit of the ventilator, showing the narrow air passages between its walls and the wall of the attachment.

In the drawing, 2 represents the upper portion of a ventilator or flue and 3 an elbow mounted for rotary movement thereon and having preferably a ball bearing 4 on the upper portion of the ventilator. The upper end of the elbow is laterally turned to form a substantially horizontal extension 5 having an exit opening 6 through which the currents of air are discharged. It is my object in this invention to increase the natural suction or draft in the exit of the elbow, for the purpose of providing better ventilation in the room or space with which the ventilator is connected, and with this end in view I provide a ring 7, made preferably of sheet metal in the form substantially of a truncated cone. This ring encircles the end 5 of the elbow and projects

outwardly beyond the exit opening therein, a narrow annular gap 8 being formed between the converging walls of the ring 7 and the edge of the exit opening 6. The ring is mounted on the elbow, preferably by means of clips 7'. The currents of air striking the inner surface of the ring will be directed by the walls thereof through the annular passage 8 and into the path of the currents of air flowing from the ventilator, the inclination of the walls of the ring having the effect of directing the air currents toward the center of the exit opening of the elbow. The end portion of the elbow encircled by the converging walls of the ring, is of uniform diameter so that the currents of air flowing through the elbow will not be retarded at any point, but may flow freely without choking or causing any back pressure in the elbow, and the tapered walls of the ring are parallel with a line drawn tangentially with respect to the end of the elbow to direct the currents of air flowing through the annular passage to a point near the exit opening of the elbow, where a sufficient suction will be formed to draw the unobstructed air currents through the exit opening of the elbow.

For the purpose of hastening the discharge of the products of combustion and increasing the suction in the ventilator, I prefer to provide means for imparting a rotary movement to the air currents, said means consisting preferably of a series of blades 9 obliquely mounted on the inner surface of the cone-shaped ring and extending from end to end thereof. These blades and the smaller end of the ring 7 project beyond the open end 6 and the blades form with the ring and the wall of the flue a series of narrow air passages, the oblique arrangement of the blades operating to impart a rotary movement to the air currents passing through said ring and between said blades and to the air currents flowing from the flue, and increase the velocity of the discharge of such currents. The air currents flowing out of the elbow and striking the walls thereof would be, under ordinary conditions, retarded to a considerable extent by contact with such walls, but the revolving air currents will set up such a suction at the mouth of the flue that the air discharged from the flue will be drawn inwardly, away from the ventilator, and the flow through the ventilator materially hastened. The

blades 9 may be any suitable distance apart and their shape may be varied and still be within the scope of my invention.

I claim as my invention:

- 5 A ventilator comprising an elbow mounted for rotary movement on a vertical axis and having an exit opening, a ring in the form of a truncated cone encircling the outer end of said elbow and said exit opening, the tapered walls of said cone being obliquely arranged with respect to the end of said elbow and spaced therefrom, an unobstructed annular air passage being thereby formed between said cone and elbow, the
- 10 walls of said cone directing such air currents inwardly to create a suction through
- 15

the exit opening of said elbow, the opening in the discharge end of said cone being of greater diameter than the adjacent opening in said elbow to prevent choking of the air currents passing therethrough, and substantially straight blades mounted obliquely on the inner surface of said cone and extending substantially from end to end thereof and converging from their rear toward 25 their forward ends to impart a rotary movement to the currents of air passing between said cone and elbow.

In witness whereof I have hereunto set my hand this 16th day of January, 1917. 30

FRANK C. SMITH.
